UNITED STATES PATENT OFFICE.

WILLIAM P. FITZGERALD, OF BROOKLYN, NEW YORK, ASSIGNOR TO CROUCH & FITZGERALD,
A CORPORATION OF NEW YORK.

TRUNK-TRAY.

No. 906,124.

Specification of Letters Patent.

Patented Dec. 8, 1908.

Application filed February 28, 1908. Serial No. 418,254.

To all whom it may concern:

Be it known that I, WILLIAM P. FITZGERALD, a citizen of the United States, and a resident of the borough of Brooklyn, county 5 of Kings, and State of New York, have invented certain new and useful Improvements in Trunk-Trays, of which the following is a specification.

This invention relates to trays for trunks 10 and seeks to provide a tray of increased durability and rigidity without undue weight.

It also seeks to provide a tray specially arranged to carry fragile articles such as china and glassware, and to this end, the 15 tray is provided with a padded interior and padded adjustable partitions.

In the accompanying drawings forming 20 part of this specification in which like reference numerals designate corresponding parts,—Figure 1 is a perspective view showing a tray embodying the invention; Fig. 2 is a perspective view of one end of a partition; Fig. 3 is a plan view partly in section; Fig. 4 is a sectional elevation on the line 25 4—4 of Fig. 1, partly broken away; and Fig. 5 is a fragmentary sectional view on the line 5—5 of Fig. 1.

The tray bottom 1 and the four end walls 2, 3, 4 and 5 are connected together in the 30 usual way, and are also provided preferably at suitable places with angle stays such as 6, 7, 8 and 9. The end walls 2 and 3 terminate in an upward marginal portion bent inward to increase the rigidity of said end 35 walls and these marginal portions form part of said end walls. The end walls are also provided with transversely extending stays, such as 10, 11 and 12, secured to the tray bottom. These stays are preferably loop-shaped and may be secured to the bottom 40 of the tray in any suitable manner. In the preferred arrangement of these stays and as shown in the drawings, one side 13 of the loop extends across the outer face of the end 45 wall 3 and has its free end 14 bent at an angle to lie against the outer face of the bottom of the tray to which it is secured by a rivet 15. The other side 16 of the loop extends downward and has its free end bent at 50 an angle and secured by a rivet 17 to the inner face of the tray bottom.

18 is an inner upright face piece extending from the top of each end wall 2, 3 to the tray bottom and provided with partition spacers 55 19 to receive the adjustable partitions 20.

These partitions have their sides covered with padding 21, but leaving their ends unpadded so as to be readily received between the spacers 19. The end walls 4 and 5 are covered on their interior with pads 22 and 60 the bottom is covered on its interior with a pad 23. These pads preferably consist of an inner wall of cardboard, such as 24, an outer wall of canton flannel 25, and filling of suitable material, such as cotton. The inwardly bent upper marginal portion of the end walls provides an economical means for increasing the rigidity of said end walls. The rigidity of these walls is further increased by the stays, such as 10, 11 and 12, 65 and also by the upright face pieces 18. As heretofore made, trunk trays are especially weak in their end walls. Strength is necessarily sacrificed to lightness. In the present invention, the tray is greatly strengthened 70 especially in its end walls with very little increase in its weight and this is accomplished without unduly adding to the cost of the tray. The pads are preferably glued in place.

What is claimed, and what is desired to be secured by United States Letters Patent 75 is:

1. A trunk tray having end walls terminating in an upper marginal portion bent inward to increase the rigidity of said end walls and forming part of the same, and transversely extending loop-shaped stays for said end walls secured to the tray bottom.

2. A trunk tray having end walls terminating in an upper marginal portion bent inward to increase the rigidity of said end walls and forming part of the same, and inner upright face pieces extending from the tops of 85 said end walls to the tray bottom.

3. A trunk tray having end walls terminating in an upper marginal portion bent inward to increase the rigidity of said end walls and forming part of the same, and inner upright face pieces extending from the tops of 90 said end walls to the tray bottom and provided with partition spacers.

4. A trunk tray having end walls terminating in an upper marginal portion bent inward to increase the rigidity of said end walls and forming part of the same, and transversely extending loop-shaped stays for said 95 end walls secured to the tray bottom, said tray being also provided with suitably located angle stays for the walls thereof.

5. A trunk tray having end walls terminating in an upper marginal portion bent inward to increase the rigidity of said end walls and forming part of the same, and transversely extending stays for said end walls secured to the tray bottom, said tray being provided with inner upright face pieces extending from the tops of said end walls to the tray bottom.
- 10 6. A trunk tray having end walls terminating in an upper marginal portion bent inward to increase the rigidity of said end walls and forming part of the same, and transversely extending stays for said end walls 15 secured to the tray bottom, said tray being provided with inner upright face pieces extending from the tops of said end walls to the tray bottom, and provided with partition spacers.
- 20 7. A trunk tray having a padded interior and padded adjustable partitions and also having end walls terminating in an upper marginal portion bent inward to increase the rigidity of said end walls and forming part of 25 the same, and transversely extending loop-shaped stays for said end walls secured to the tray bottom.
8. A trunk tray having a padded interior and padded adjustable partitions and also having end walls terminating in an upper marginal portion bent inward to increase the rigidity of said end walls and forming part of the same, and inner upright face pieces extending from the tops of said end walls to the tray bottom.
- 35 9. A trunk tray having a padded interior and padded adjustable partitions and also having end walls terminating in an upper marginal portion bent inward to increase the rigidity of said end walls and forming part of the same, and transversely extending stays for said end walls secured to the tray bottom, said tray being provided with inner upright face pieces extending from the tops of said end walls to the tray bottom, and provided with partition spacers.
